US00D616915S

(12) **United States Design Patent**
Silveria et al.

(10) **Patent No.:** **US D616,915 S**
(45) **Date of Patent:** **** Jun. 1, 2010**

(54) **SAFETY GOGGLE**

(75) Inventors: **Ricardo Silveria**, Bridgewater, MA (US); **Wayne Gleason**, W. Greenwich, RI (US); **Aaron Szymanski**, Thomaston, CT (US); **Michael Mennone**, Guilford, CT (US); **David Seebauer**, Southington, CT (US); **Glen Vincent**, Torrington, CT (US)

(73) Assignee: **Sperian Eye & Face Protection, Inc.**, Smithfield, RI (US)

(**) Term: **14 Years**

(21) Appl. No.: **29/351,213**

(22) Filed: **Dec. 2, 2009**

(51) LOC (9) Cl. **16-06**

(52) U.S. Cl. **D16/312**

(58) Field of Classification Search **D16/101, D16/300-342; D29/109-110; D24/110.2; 351/41, 44, 51-52, 62, 158, 92, 103-123, 351/140, 153, 45-46; 2/426-432, 447-449, 2/441, 434-437, 13, 15; D21/483, 659-661**

See application file for complete search history.

(57) **CLAIM**

The ornamental design for safety goggle, as shown and described.

DESCRIPTION

FIG. 1 is a front perspective view of the safety goggle in accordance with the present invention;

FIG. 2 is a front view thereof;

FIG. 3 is a rear side view thereof;

FIG. 4 is a right side view thereof;

FIG. 5 is a left side view thereof;

FIG. 6 is a top view thereof;

FIG. 7 is a bottom view thereof; and,

FIG. 8 is another front perspective view showing an optional prescription insert in broken lines.

The elements shown in broken line are illustrated for environmental purposes only, and form no part of the claimed design.
